UNITED STATES PATENT OFFICE.

ROBERT N. EGGLESTON, OF MUSKOGEE, OKLAHOMA, ASSIGNOR TO PULL-U-OUT MANUFACTURING COMPANY, OF ST. LOUIS, MISSOURI, A CORPORATION OF MISSOURI.

HOISTING AND PULLING MECHANISM.

1,177,767.

Specification of Letters Patent.

Patented Apr. 4, 1916.

Application filed May 29, 1914. Serial No. 841,900.

To all whom it may concern:

Be it known that I, ROBERT N. EGGLESTON, citizen of the United States, residing at Muskogee, in the county of Muskogee and 5 State of Oklahoma, have invented certain new and useful Improvements in Hoisting and Pulling Mechanism, of which the following is a specification.

This invention relates to hoisting and 10 pulling mechanisms, and has for its main object to provide a small, light-weight, manually-operable mechanism that can be used successfully for lifting great weights or exerting a strong pull on a device which it is 15 desired to move.

Another object is to provide a hoisting and pulling mechanism that comprises a block and tackle and manually-operable winding device or windlass combined as a 20 single unit and constructed in such a manner that the complete mechanism can be carried in the tool box or other small compartment of an automobile when it is not in use.

25 Other objects and desirable features of my invention will be hereinafter pointed out.

In the drawings: Figure 1 is a perspective view of my invention employed in extracting 30 a self-propelled vehicle from a mud-hole; Fig. 2 is a top plan view of the windlass mechanism; Fig. 3 is a perspective view of the entire device folded to its most compact form for shipment or storage; Fig. 4 35 is a fragmentary sectional view taken on the line 4—4 of Fig. 2; Fig. 5 is a fragmentary sectional view taken on the line 5—5 of Fig. 4; Fig. 6 is a fragmentary perspective view of the pawl and ratchet mechanism 40 employed in connection with the operating lever showing the parts disassembled.

Corresponding and like parts are referred to in the following description and indicated 45 in all the views of the drawings by the same reference characters.

My improved device consists principally of a new and improved type of manually operable windlass or cable winding apparatus, indicated as a whole by the numeral 50 10. This windlass includes a frame comprising spaced side members 11 and 12, preferably in the form of metal straps provided along their outer faces with longitudinally

extending reinforcing ribs 13, in order to 55 insure the maximum strength with the least weight and having their end portions bent toward each other and secured by bolts 14 and nuts 15.

As best shown in Fig. 2, it will be seen 60 that the straps 11 and 12 have their end portions thickened to form reinforcing heads to receive the securing bolts 14 and that the end portions at one end of the frame which they form, extend for a considerable distance in parallel spaced relation to each other. These straps are provided intermediate their length with lateral projections or guard arms 16, the free ends of which are directed inwardly to overlap each 70 other, being mortised as shown at 17 for close interlocking engagement, a screw 18 or other fastening device being threaded through their overlapping ends to secure them together. These guard arms 16 form 75 a yoke-shaped device that serves not only as guard, but also as a brace for the inner portions of the side members of the frame. An idler pulley 19, peripherally grooved to receive a cable, is journaled upon a shaft 20 80 mounted in bearings 21 formed adjacent the forward end of the frame 10.

The side members of the frame, adjacent the guard arms 16, are thickened exteriorly to provide bearings 22 for a shaft 23 upon 85 which is journaled the winding drum of the windlass, indicated as a whole by the numeral 24. This winding drum, as best shown in Figs. 4 and 5 of the drawings, is cast or otherwise formed in a single piece 90 of metal, one side face being formed with an annular recess or chamber providing a central hub portion 25 and peripheral cable receiving portion 26 connected to the hub by the body plate 27. The peripheral portion 26 of the winding drum is provided at its edges with outwardly directed cable retaining flanges 28 and interiorly with teeth 29 forming in effect an internal gear.

The side member 11 of the frame is 100 thickened interiorly to provide a bearing 30 in which is journaled a shaft 31, the inner end of which carries a pinion 32 meshing with the internal gear 29. A crank handle or operating lever, indicated as a 105 whole by the numeral 33 is mounted to turn freely upon the shaft 31 and is held against disengagement therefrom by a ratchet wheel

34 pinned or otherwise secured against longitudinal movement from the squared outer end of the shaft 31. The crank handle 33 includes a body portion 35 and handle portion 36, the body portion at its free end being constructed in the form of a sleeve 37 through which the shank or body portion of the handle member 36 passes, this handle member being provided at its free end with 10 a handle 38. The two handle sections are secured in adjusted relation to each other by means of a wing bolt 39, as clearly shown in Fig. 2 of the drawings.

The inner face of the body portion 35 of 15 the crank handle is provided with a medial, longitudinally extending reinforcing shoulder 40 and such crank handle member, adjacent that end engaging about the shaft 31, is off-set inwardly providing an exterior 20 shoulder 41 in which is formed a longitudinal socket 42. The stem or shank portion 43 of a reversible locking pawl 44 extends in this socket and is normally held in outermost position by a helical spring 45 seated 25 in the socket. This stem 43 of the pawl has an enlarged laterally directed head 46 forming a finger piece by means of which the pawl may be manually retracted and its position reversed, as will be later explained, 30 and this extension, at a point substantially in alignment with the stem or shank of the pawl, is provided with a transverse pawl shoulder 47 having one vertical and one inclined face, as clearly shown in Fig. 6 of 35 the drawings. The pawl stem at that side diametrically opposite the extension 46, is provided with a radially extending locking pin 48 adapted, under certain circumstances, to be swung to seat in a transverse groove 49 40 formed in the outer face of the body portion of the crank handle.

In addition to the above described pawl, controlling the rotation of the shaft 31 upon turning of the crank handle, I provide a 45 second pawl, indicated as a whole by the numeral 50 which engages directly with the teeth of the pinion 32 when in active position. This pawl is pivoted intermediate its length upon a pivot pin 51 passed through 50 the upward extension or guard arm 16 of the frame member 11, immediately above such frame member and has one end offset inwardly, as shown in dotted lines in Fig. 5, to extend into the plane of the pinion and 55 then curved downwardly to form a pinion tooth engaging terminal 52. The opposite end of the pawl is provided with an outwardly directed extension or finger piece 53 by means of which the pawl may be 60 swung into or out of engagement with the pinion. The pawl is provided, substantially concentrically with respect to its pivot 51, with an arcuate shoulder 54 notched as shown at 55 to receive the rebent terminal 65 of a leaf locking spring 56 when the pawl is

in inactive position, as shown in Fig. 4. When the pawl is swung to active position, the terminal 56 rides out of this notch to engage against the rear face of the shoulder and hold the pawl in engagement with the pinion. This leaf spring is secured at its opposite end to a stud 57 extending inwardly from the same guard arm supporting the pawl 50, by a screw or other fastening device 58. The active terminal or pinion engaging 75 end of the pawl is so shaped that when the pawl is in active position, it will permit ready rotation of the pinion in one direction, but hold it against reverse turning.

One end of a wire cable 59 is secured to 80 the winding drum 24 in any suitable manner, such as by passing such end through one of the cable retaining flanges 28 and bolting or riveting such end to the outer face of the body forming plate 27 of the drum. 85 The greater portion of this cable is wound about the drum, when the device is not in use, and the other end is passed about one of the pulleys 60 of a double pulley block 61, back about the idler pulley 19, from 90 there about the other pulley 62 of the pulley block and is then secured by any suitable form of clamp 63 to the adjacent end of the frame of the windlass.

In addition to the above described wind- 95 lass structure, my complete mechanism, when used for extracting vehicles from mud-holes, includes a chain or cable 64 provided at its ends with hooks 65, a second chain or cable 66 provided at one end with a hook 100 67, and one or more land anchors 68. These land anchors are each preferably formed from a single piece of metal including a body portion terminating at one end in a widened piercing point 69 and at its opposite end in a widened head 70 having a claw 71 between the fingers of which a chain link may be positioned.

In employing the above described device 110 to draw a vehicle out of a mud-hole or sand pit, the operator first drives one or more of the land anchors or stakes into the earth as far in advance of the vehicle to be extracted as the length of the cable 59 and chains 64 and 66 will permit. The land anchors are 115 driven into the ground with their upper ends inclined toward the vehicle to be extracted and if more than one anchor is employed, they are spaced a slight distance apart, usually 15 to 20 inches from each other. One of the hooks 65 of the chain 64 is then 120 engaged in the rear end of the frame of the windlass device 10, as shown in the drawings, and its opposite end secured to the vehicle in any suitable manner, a simple way being to pass it about the forward axle 72 of the vehicle and secure it by engaging the other hook 65 through one of the chain links. The locking pawl 50 is then swung out of 125 engagement with the pinion 32 and the hand 130

crank locking pawl 44 moved to inoperative position by forcing its stem into the socket 42 until the pin 48 is opposite the slot 49 and then swinging the pawl to seat the pin in the slot. In this position, the ratchet wheel engaging shoulder 47 of the pawl is held in spaced relation to the ratchet wheel, under which circumstances, the cable drum is free to turn without hindrance and without movement of the crank handle. The cable is then unwound from the drum by pulling upon the block and tackle 61, after which the hook 67 of the chain 66 is inserted through the eye of the block and tackle and the chain secured between the claws of the land anchors in the manner shown in Fig. 1. The set bolt 39 is loosened to permit withdrawal of the portion 39 of the crank handle from the sleeve 37, such portion at this time being so mounted in the sleeve that the hand grip 38 is directed inwardly toward the windlass frame, as shown in Fig. 3. The hand crank portion 36 is then inserted in the manner shown in Figs. 1 and 2 of the drawings and secured in place by tightening the bolt 39, the length of the handle, as a whole, being readily adjusted by moving the handle portion 36 through the sleeve 37 before tightening of the bolt.

After the above operations have been performed, the pawl 50 is thrown into active position and the pawl 44 released by swinging the pin 48 out of the slot 49. This latter pawl is then turned to such a position that it will lock the shaft 31 against such movement as would permit unwinding of the cable 59 from the winding drum and the cable is wound upon the drum by turning the hand crank 38. This winding of the cable upon the windlass, which is anchored by means of the land anchors, results in drawing the vehicle toward the land anchors, and consequently out of the mud-hole or sand pit. Because of the employment of the pinion 32 with the internal gear 29, great leverage is obtained and but little effort is required to extract the vehicle, irrespective of how badly mired it may be. This leverage is still further increased of course by the manner in which the cable is trained about the pulleys of the block and tackle, the winding drum and the pulley 19 of the windlass.

After the vehicle has been drawn out of difficulty, the chains 66 and 64 are disconnected from the windlass and from the land anchors and vehicle axle, respectively, and the land anchors drawn from the ground. The hand crank is then turned to wind up any remaining slack cable, bringing the block and tackle 61 into direct engagement with the winding drum, as best shown in Fig. 3 of the drawings, after which the handle carrying portion of the hand crank is again freed from the sleeve and replaced in reverse position in order that the crank may

be swung to the position shown in Fig. 3 with the handle proper extending transversely of the windlass frame and thereby occupying practically no space.

It might be well to state at this point that, in case it becomes difficult to draw the cable from the winding drum merely by pulling upon the block and tackle, the pawl 44 may be swung to reverse position to that which it occupies when winding the cable and with the pawl 50 released, the hand crank may be turned to rotate the drum and facilitate the unwinding of the cable therefrom. The intermediate portion of the slot 49 is preferably notched as shown at 73 to provide a seat for the pin 48 to prevent casual disengagement of the pawl 44 when the latter is locked in inactive position.

From the foregoing description, it will be apparent that I have provided a simply constructed device which is strong, readily operated and durable and which, above all, when folded to the position shown in Fig. 3 of the drawings, is extremely compact, occupying but little more space in the tool box of the vehicle than would a coil of wire cable of the length contained upon the drum if wound by hand, this being due to the fact that it is almost impossible to tightly wind such cable, save by the use of considerable force in connection with a winding drum.

Stakes or land anchors of the type disclosed, when applied in the manner illustrated in Fig. 1 of the drawings, offer remarkable resistance to their withdrawal, when in use, due to the fact that being driven into the ground until their claws are substantially flush with the surface, the enlarged heads 70 in effect form fulcrums about which their lower ends must swing before they can be drawn out by strain applied in any direction other than the direction of their length. For this reason, comparatively small land anchors, not over 10 and 12 inches in length, are found to be sufficient.

Although I have described the windlass structure in connection with land anchors and chains for extracting vehicles from mud-holes and other like difficulties, it will of course be understood that I do not wish to limit it to such use as it may be employed for hoisting purposes, wire stretching, or in fact for any purpose for which it may prove to be adapted, without in the slightest degree departing from the spirit of my invention. Furthermore, while I have herein illustrated and described a land anchor of novel construction and also a novel method of anchoring a pulling device to the ground, I make no claim in this application to either of the above features, as they form the subject-matter of my pending application Serial No. 841,899, filed May 29, 1914. Furthermore, the chains 64 and 66 may be

hooked together and employed as a tow rope to haul a broken down vehicle to a garage, or shop.

Having thus described the invention, what is claimed as new is:

1. A hoisting and pulling mechanism, comprising a frame provided with spaced side members, an idler pulley arranged between said side members at one end of the frame, a device on said frame arranged in longitudinal alinement with said pulley to which one end of a block and tackle can be connected, a hollow drum rotatably mounted on said frame between the side members thereof and provided with an internal gear, said drum being arranged in longitudinal alinement with said pulley, a shaft on said frame provided with a pinion that meshes with said internal gear, and an operating mechanism for said shaft comprising a manually-operable lever that can be arranged in parallel relation with the side members of said frame when the mechanism is not in use.
2. A hoisting and pulling mechanism, comprising a frame provided with spaced side members, a yoke-shaped device arranged at right angles to said side members and acting to reinforce and strengthen the intermediate portions of same, a hollow drum rotatably mounted on said side members and arranged between the side

portions of said yoke-shaped device, an internal gear on said drum, a pinion carried by said frame and meshing with said gear, a manually-operable actuating means for said pinion, means at one end of said frame to which a block and tackle can be connected, and means at the opposite end of said frame to which a stay or securing device can be connected.

3. A windlass mechanism including spaced frame forming straps having their end portions offset toward each other to extend in parallel spaced relation, means connecting such end portions including a pulley rotatably mounted between adjacent end portions, upwardly directed guard arms carried one by each strap and having inwardly directed over-lapping terminals connected to each other, a shaft mounted in the strap members adjacent their juncture with the guard arms, a cable receiving winding drum mounted upon the shaft, whereby the guard arms guide the cable during its winding upon or unwinding from the drum, and means for rotating the drum.

In testimony whereof I affix my signature in presence of two witnesses.

ROBERT N. EGGLESTON. [L. S.]
